ELECTRIC CONDUCTOR FOR ELECTRIC MACHINES AND APPARATUS

Application filed July 8, 1927, Serial No. 204,216, and in Czechoslovakia July 16, 1926.

This invention relates to electric conductors for electric machines and apparatus. It has already been proposed to subdivide conductors of this class having a comparatively large transverse sectioned area into a plurality of individual conductors connected with each other in parallel and insulated from each other for the purpose of reducing the skin effect, and for preventing a non-uniform distribution of the current over the entire transverse section of the conductor, more particularly if such conductors are located in grooves of electric machines, or are subject to external magnetic actions. The problem to be solved by such conductors is to so arrange the individual conductors, that the electro-motive forces induced in the same are equal as nearly as possible and that no equalizing currents are set up between the same and the losses resulting from such equalizing currents are avoided.

The object of the present invention is to solve this problem for conductors composed of a plurality of groups located side by side, each of such groups comprising a plurality of superposed individual conductors. With this object in view the present invention consists essentially in that each individual conductor is provided with at least one bend extending from one individual conductor over the top of its own group, then laterally downwards and then across the bottom of the groups to another group in which the said individual conductor continues.

Fig. 1 of the drawing shows by way of example a constructional form of an electric conductor embodying the present invention; Fig. 2^a is a plan view, Fig. 2^b is a vertical and Fig. 2^c is a lateral view of part of an individual conductor. Figs. 3^a, 3^b, 3^c are similar views of a modified individual conductor; Fig. 4 illustrates another constructional form of an entire conductor according to the present invention; Fig. 5^a is a plan view and Fig. 5^b is an end view of part of an individual conductor.

In Fig. 1 an electric conductor is shown which comprises two groups 1, 2 of conductors, each group comprising a plurality of superposed individual conductors. These in-

dividual conductors pass step by step from one level to another in the composite conductor and simultaneously from one group of the individual conductors to the other group. This is effected by providing the individual conductors with bends α so shaped that they pass first across the group of the individual conductor, then laterally downwards then across both groups and end in a straight portion forming part of the other group. A suitable form of the bend α of a band shaped individual conductor for this constructional form of the entire conductor is shown in Figs. 2^a, 2^b and 2^c and also in Figs. 3^a, 3^b, 3^c. In Figs. 2^a, 2^b, 2^c the bend α of an individual conductor is shown in three different views, and is so shaped that the individual conductor passes from the top of the group 1 to the bottom of group 1. In Figs. 3^a, 3^b, 3^c, a bend α of an individual conductor is shown which bend is so shaped that the individual conductor passes from the top of group 1 to the bottom of group 2. It will be noted that according to the invention all bends are of the same length, so also all the individual conductors have the same length throughout per unit of length of the entire conductor.

In Fig. 4 an electric conductor is shown having four groups located side by side each group being formed by a plurality of superposed individual conductors. In this case again the individual conductors change positions step by step, the bends α being so shaped that the individual conductors of any of the outer group, say of the group 1 extend on top over their own group, pass downwards laterally and extending across the bottoms of all groups pass into the other outer group, say 4. The bends of the two inner groups, say of the group 2 are so shaped that the bend of each individual conductor extends over the top of its own group and the adjacent outer group, passes downwards laterally and then across the bottoms of the groups up to the other inner group, say 3 into which it enters. The bends of all individual conductors follow each other in such a manner that the bends of each individual conductor are at equal distances from each other. The shape of all individual conductors

tors of the example illustrated in Fig. 4 prior to forming therein the bends for varying their level is shown in Fig. 5. The lengths of the bends of all individual conductors and also of each individual conductor per unit of length of the entire conductor are again equal.

The details of the construction and combination of the individual conductors and the entire conductors built up therefrom may be varied without departing from the essence of my invention. Thus instead of the band shaped individual conductors shown also individual conductors of another transverse section or wires may be used and the individual conductors may be insulated from each other in any desired manner.

The manufacture of the entire conductors according to the present invention is very simple as will be readily understood from the drawing. Also the insulation between the individual conductors and the insulation of the bends may be readily provided for. The conductors are of sufficient mechanical strength and safety against short circuiting even if they comprise a plurality of groups as above described.

What I claim is:

1. In an electric conductor the combination of two groups of superposed individual conductors, such groups being located side by side, each individual conductor being provided with at least one bend extending from one individual conductor over the top of its own group, then laterally downwards and then across the bottom of both groups to the second group in which the said individual conductor continues.

2. In an electric conductor the combination of four groups of superposed individual conductors, such groups being located side by side, each individual conductor being provided with at least one bend extending from one individual conductor of one outer group over the top of its group, then laterally downwards, then across the bottom of all four groups to the other outer group where such individual conductor continues and each individual conductor of an inner group having at least one bend extending across the top of its own group and the adjacent outer group, then laterally downwards, then across the bottoms of the groups up to the other inner group where such individual conductor continues.

3. In an electric conductor the combination of several groups of superposed individual conductors, such groups being located side by side, each individual conductor being provided with at least one bend extending from one individual conductor over the top of its own group, then laterally downwards and then across the bottom of the groups to another group in which the said individual conductor continues.

4. In an electric conductor the combination of an even number of groups of superposed individual conductors, such groups being located side by side, each individual conductor being provided with at least one bend extending from one individual conductor of one outer group over the top of its group, then laterally downwards, then across the bottom of all groups to the other outer group where such individual conductor continues and each individual conductor of any inner group having at least one bend extending across the top of its own group and the adjacent outer group, then laterally downwards, then across the bottoms of the groups up to the other inner group where such individual conductor continues.

5. In an electric conductor the combination of an even number of groups of superposed individual conductors, such groups being located side by side, each individual conductor being provided with at least one bend extending from one individual conductor over the top of its own group then laterally downwards, then across the bottom of the groups and continuing at the bottom of another group, the composite conductor consisting of halves relatively turned through 180 degrees.

In testimony whereof I affix my signature.

LUDWIG KOUBA.
